UNITED STATES PATENT OFFICE.

ALEXANDER LAWRENCE CURRIE, OF SOREL, QUEBEC, CANADA.

RAILWAY-SIGNAL.

1,320,380.

Specification of Letters Patent. Patented Nov. 4, 1919.

Application filed December 8, 1916. Serial No. 135,813.

To all whom it may concern:

Be it known that I, ALEXANDER LAWRENCE CURRIE, a subject of the King of Great Britain, and resident of Sorel, in the Province 5 of Quebec, in the Dominion of Canada, have invented certain new and useful Improvements in Railway-Signals, of which the following is the specification.

This invention relates to a portable rail-way signal particularly adapted for use in flagging trains. In the present railway practice manual flagging is commonly employed, but more often the flag is mounted on a stick which is stuck in the ground, on 10 that side of the track which comes under the observation of the engineer, and this latter system of flagging has resulted in serious accidents taking place, due to the flag falling or becoming inadvertently displaced or 15 even trailing in the wind, so that it fails to notify the engineer of an oncoming train that the track is unsafe.

Where double tracks are in use with the trains running on the left hand track the 20 flag is situated between the tracks so that it is quite impossible for the engineer of an approaching train to tell which track the signal covers and this frequently causes undue delay in the train service.

With manual flagging error in the personal equation is liable to cause accidents to happen and the objects of the present invention are to eliminate those risks of accidents, and permit of the signal being attached to the under flange of the rail in 35 such a manner that it is clear of the track but still maintains a prominent position on that side which comes under the observation of the engineer.

Further objects are to render the signal compact in construction so facilitating transportation, to permit of metallic flags of different types used in railway practice being readily mounted thereon, to adapt the 40 signal for night use, and generally to render the signal fool-proof and adapt the several parts to better perform the functions required of them.

With the above and other objects in view, 45 the invention consists essentially of the improved construction particularly described and set forth in the accompanying specification and drawings forming part of the same.

In the drawings,

Figure 1 is a fragmentary perspective

view of a rail showing the improved signal attached thereto.

Fig. 2 is a front elevation partly sectional of the improved signal. 60

Fig. 3 is a fragmentary vertical section through the flag supporting member.

Fig. 4 is an enlarged section of the tubular arm and flag supporting rod.

Like characters of reference refer to like 65 parts in the several figures.

Referring to the drawings, A represents a rail of a track, and B the improved signal attached thereto. This signal consists of a base portion 10, carrying an upwardly and angularly disposed tubular arm 11, provided with a set screw 12 extending through the wall and near the top thereof. The base 10 terminates at the end in a U-shaped flange 13 adapted to embrace one edge of the lower flange of the rail A, the said base being provided intermediate of its ends with a slot 14, the object of which will be made clear hereafter. 80

Operatively mounted on the base 10 is a clamping member 15, having that edge adjacent to the rail A offset so that it will engage with the lower flange thereof and abut against the web of the rail, the said clamping member having its other end upturned as shown at 16 and provided with an offset tongue 17 adapted to slidably engage with the slot 14 and embrace one end thereof. This clamping member is provided intermediate of its length with a slot 18 which slidably engages with the bolt 19 adapted to secure the said clamping member in the desired position. 85

Slidably mounted in the tubular member 95 11 is a rod 20 which may be secured at the desired height by tightening the set screw 12 thereon, the upper end of the rod being bent over as shown at 21 to form a U-shaped lamp supporting member 22 which is arranged in front of the metallic flag or disk 23 secured to the said rod. 100

This disk 23 is provided with a peripheral recess 24 which embraces the lateral edges of the offset portion 21 and is further 105 provided with a concentric orifice 25 with which the bolt 26 passing through the rod 20 is adapted to engage.

When the signal is in use the U-shaped end 13 of the base 10 is engaged with the 110 inner edge of the lower flange of the rail A while the clamping member 15 is adjusted

so that it engages the outer edge of the said flange with the end of the said clamping member abutting the web of the rail. The bolt 19 is now tightened so securing the 5 clamping member in the desired position to rigidly support the signal from the rail.

The type of flag to be utilized is now placed upon the rod 20 with the bolt 26 passing therethrough, and the peripheral recess 10 24 engaging with the offset portion 21, whereupon the rod 20 is elevated to the desired extent and the set screw 12 is tightened, completing the assembly of the signal.

To prevent the rod 20 from being inadvertently withdrawn from the tubular arm 11, I provide a flange 27 on the rod adapted to engage with the inturned upper end of the said arm if the arm is elevated to its extreme upper position, but it will be understood that when in operation the set screw 15 12 will maintain the rod 20 rigidly in position and so prevent the flag 23 from being rotated parallel to the track due to wind or other pressure.

20 25 For night use or foggy weather, a lamp of the proper color is suspended or hung from the hook 22 on that side facing the direction from which the train is approaching so that in double track operation of the type 30 above described, trains on the clear line are not held up or delayed.

It will be appreciated that by offsetting the tubular arm 11, the metallic flag 23 will be maintained clear of the railway track, 35 which at all times remains operative while at the same time the flag is so prominently situated that it will be readily recognized by the engineer of the approaching trains.

From this description it will be seen that

I have invented a signal which may be attached to a rail with a minimum of time and labor and will then be maintained in such a position that the engineer of a train is always notified of the state of the track, the said signal not being liable to be displaced or blown down, or trailing in the wind and in which the metallic flag may be readily interchanged to suit the requirements of the railway system.

As many changes could be made in the above description and many apparently widely different embodiments of my invention within the scope of the claim constructed without departing from the spirit or scope thereof, it is intended that all matter contained in the accompanying specification and drawings shall be interpreted as 50 illustrative and not in a limiting sense.

What I claim as my invention is:

A railway signal comprising a supporting 60 member having its base portion passing under and secured to one side of a rail and having flag carrying means on the other side of the rail and a member slidably held on the flag side of the base portion for further securing the support to the rail, one end of the slide being bent to fit the flange of the rail and the other end being upturned to form a finger hold and a downwardly offset tongue on said slide adapted to slidably engage with a slot in the base portion for limiting the movement of the slide in one direction in relation to the base portion, 65 substantially as described.

In witness whereof I have hereunto set 70 my hand.

ALEXANDER LAWRENCE CURRIE.
